UNITED STATES PATENT OFFICE.

ALFRED K. PEHRSON, OF BELLEVUE, AND KARL O. WINELL, OF PITTSBURGH, PENNSYLVANIA, ASSIGNORS TO PRESSED STEEL CAR COMPANY, OF PITTSBURGH, PENNSYLVANIA, A CORPORATION OF NEW JERSEY.

ARTICULATED CAR.

Application filed September 1, 1925. Serial No. 53,793.

This invention relates to transportation cars and particularly to railway cars of the articulated unit type in which each unit comprises a plurality of car bodies, the adjacent 5 ends of two of which are carried by a single truck, and has for an object the provision of a safe and weather proof vestibule or passageway between the bodies.

Another object of the invention is to provide a passageway member between the adjacent ends of two bodies of an articulated car unit which will permit relative movement between said ends and still maintain an unobstructed passageway between said 15 bodies.

Another object of the invention is to provide the adjacent ends of two bodies of an articulated car unit with automatically adjustable weather proofing means adapted to 20 engage a vestibule or passageway member positioned between the bodies, regardless of the position of the bodies relative to each other and to the vestibule or passageway member.

Another object of the invention is to provide a novel end plate and hood construction for the end of a body of an articulated car unit.

Another object of the invention is to provide a roof for a passageway member of an articulated car unit with novel drainage means.

Another object of the invention is to provide the adjacent ends of two bodies of an articulated car unit with hoods which cooperate with the roof or top of a vestibule or passageway member, positioned between said ends, to form a weatherproof seal between the hoods and roof of the vestibule or 40 passageway member.

These and other objects will be apparent from the following description.

Referring to the drawings in which like reference characters refer to like parts Fig. 45 1 is a longitudinal sectional view of the adjacent end portions of two bodies of an articulated car unit embodying the invention; Fig. 2 is a sectional view of the same taken on the line 2—2 of Fig. 1 showing the 50 hoods of the bodies and the roof of the passageway member in plan; Fig. 3 is a cross sectional view taken on the line 3—3 of Fig. 1; Fig. 4 is a sectional view taken on the line 4—4 of Fig. 2; Fig. 5 is a sectional view

taken on the line 5—5 of Fig. 2, only a portion of the passageway member being illustrated; Fig. 6 is a sectional view taken on the line 6—6 of Fig. 5; Fig. 7 is a sectional view taken on the line 7—7 of Fig. 5; Fig. 8 is an enlarged sectional view of portion of the construction shown in Fig. 3; Fig. 9 is an enlarged sectional view taken on the line 9—9 in Fig. 4; Fig. 10 is an enlarged sectional view taken on the line 10—10 in Fig. 9; Fig. 11 is an enlarged sectional view on the line 11—11 in Fig. 2; Fig. 12 is a plan view of a modified form of roof construction for the vestibule member, and Fig. 13 is a plan view of a further modification of the same, Fig. 14 is an enlarged sectional 70 view taken on the line 14—14 of Fig. 2.

Referring now in detail to the drawings the reference character 1 indicates an articulated car unit which comprises a plurality of car bodies 2, the adjacent end portions 3 of two of which have been illustrated in the drawings. The underframe 4, of these two bodies, at their adjacent ends are provided with body center plates 5 both of which engage a truck center plate 6 mounted on a truck bolster 7, which bolster is suitably mounted in a truck (not shown) of any preferred construction. Between the end portions 3 of the bodies 2 a vestibule or passageway member 8 is provided which forms a safe and weather proof passageway between two adjacent bodies.

The underframe 4 may be of any suitable construction having the center plate 6 located at one end thereof. The superstructure framing is of any preferred construction and may comprise the usual spaced side posts (not shown) which at their lower ends are suitably connected with the underframe, and at their upper ends are connected with side plates 10.

The end 3 of each of the bodies 2 comprises end corner posts 11, each of which is connected at its lower end with the underframe and at its upper end with one of the side plates. This end also comprises spaced center end posts 12 which at their lower ends are connected with the underframe. Each of these posts is of modified Z section having a web 13 and flanges 14 and 15, such web extending outwardly from the end of the body at an angle. The flange 14 extends inwardly toward the interior of the

body and has secured thereto one end of finish plate 16, the opposite end of such plate being connected with the inner edge portion of a finish plate 17, the opposite edge portion of which is connected with the end corner post 11. The flange 15 for a portion of its length extends outwardly at a right angle to the web 13 and for the remainder of its length extends in the same direction as the web 13 and is secured to the inner ends of an end sheathing plate 18, the opposite end of such plate being connected with the post 11.

At the end of each body a roof carline 19 is provided which is preferably of angle form in cross section which extends from side to side of the body and at its ends is connected with an end plate 20 and the end portions of the side plates 10. Intermediate its ends this carline is shaped to suit the type of the roof desired, the roof illustrated in the drawings being of the clerestory type. The carline 19 has a horizontally disposed flange 21 to which the roof sheets are secured and a vertically disposed flange 22 to which the upper edge portion of an end sheathing plate 23 is secured, the lower edge portion of such plate being secured to the sheathing plate 18 and to the posts 11 and 12. The lower portion of this plate 23 is notched as indicated at 24 and the side edge portions of the plate which define the sides of the notch are secured to the flanges 15 of the posts 12.

The end plate 20 comprises a horizontally disposed portion 25 which extends from side plate to side plate and rests on and is secured to such side plates. The inner edge portion of this plate is provided with an upwardly extending flange 26 to which is secured the lower edge portion of an interior finish plate 27, the upper edge portion of this plate being secured to a roof carline 28. The outer edge portion of this end plate is provided with a curved notch 29 and on each side of this notch is provided with an upwardly extending flange 30 to which the end sheathing plate 23 is secured. To the edge portion of the end plate, which defines the notch 29, a member 31 is secured, which member is for the greater portion of its length curved to correspond to the shape of the notch. This member is preferably of channel form in cross section having a vertically disposed web 32 and top and bottom flanges 33 and 34 respectively, the upper end portions of the post 12 being secured to the web 32. Above the end plate 20 a horizontally disposed plate 35 is provided, the inner edge portions of which rests on and is secured to the flange 33 of the member 31. The outer edge portion of this plate 35, adjacent the longitudinal center line of the body, projects outwardly, some distance beyond the plane of the end sheathing, and

at its ends is tapered inwardly toward the end sheathing. This edge portion is provided with an upwardly extending flange 36 which is connected with a downwardly depending flange 37 of a roof extension or hood sheet 38. This hood sheet is provided with an upwardly extending flange 39 which is secured to the end sheathing plate 23. Between the flanges 37 and 39 and on each side of the longitudinal center line of the body the sheet 38 slopes downwardly and outwardly in the direction of the length of the body, and at its sides slopes downwardly and outwardly in the direction of the width of the body. This hood sheet is widest at its central portion and the outer edge portion, on each side of this central portion, is sloped inwardly and at its ends is secured to the end sheathing plate 23. To the outer flange 37 of the hood sheet there is secured a plate 40 which extends downwardly therefrom, the use of which will hereinafter be set forth.

To assist in strengthening the end of the car a member 41 is provided which extends in a direction transversely of the car, which member is preferably of angle form in cross section having a flange 42 directed inwardly and a flange 43 directed upwardly. The flange 42 for the greater portion of its length rests on and is secured to the plate 35, and the flange 43 throughout its length is secured to the end sheathing plate 23. At its ends this member is connected with the carline 19 through the medium of a plate 44 which is secured to the flanges 22 of the carline 19, and the flange 43 of the member 41 as shown in Fig. 14.

The passageway member 8 comprises a floor or base portion 45, a top or roof portion 46 and curved sides 47 which sides are spaced apart to provide a passageway 48, and are secured to the floor and roof portions 45 and 46 respectively. Secured to the underside of the portion 45 is a bearing plate 49 which extends into and cooperates with a bearing plate 50, which is secured to a bar 51 supported by and secured to supports 52 mounted on the truck bolster 7. The bar 51 extends transversely between the adjacent ends 3 of adjacent bodies and is disposed above the underframes 4. At each side of the member 8 the portion 45 is provided with spaced lugs 53 which depend downwardly from the bottom surface of the portion 45, the bar 51 passing between such lugs and being adapted to engage them whereby any rotary movement of the truck will be transmitted to the member 8. The bearing surface 54 of the bearing plate 49 is made in the form of a portion of a sphere in order that the member 8 may swivel in any direction to adjust itself to the relative positions of the two connected adjacent car bodies. To prevent undue swiveling move-

ments, and in so far as possible to keep the member 8 properly positioned, the portion 45 adjacent each end of the bar 51 is yieldably connected with such bar by means of 5 a bolt 55 which preferably passes through the portion 45 and through the bar 51, and a spring 56 mounted below the bar on the bolt 55 which spring is held in place by a nut 57 which nut forms a seat for the 10 lower end of the spring. The upper end of the spring 56 seats in a spring seat member 58 mounted in the bar 51. To further prevent any undue swiveling movement of the member 8 the under surface of the portion 15 45 is provided with members 59 which are adapted to engage with members 60 secured to floor members 61 which in turn are secured to the underframes 4. The upper surfaces of the floor members 61, 20 portion of the floor 62 and the portion 45 of the member 8 are in substantially the same horizontal plane. The top or roof portion 46 is of circular form in plan and has a downwardly depending annular flange 25 63 to which the curved sides 47 are secured.

Between the sides the flange 63 has secured thereto curved plates 64 which plates, as well as the upper portions of the sides 47, extend above the flange 63. The periphery of the portion 46 above the flange 63 is offset at 65 and this offset together with the upper portion of the sides 47 and plates 64 form a water conducting channel for conducting water from the portions of the member 8 which are located in recesses formed in the adjacent ends of two bodies by the construction embodied therein which have hereinbefore been fully described. Between the bodies each of the portions of the sides 30 40 which projects above the flange 63 is provided with a notch 66 which permits the water in the conducting channel to drain to the exterior of the car. The top of the member is preferably in the form of a portion 45 of a sphere the radius of which in any direction is struck from the center of the bearing surface 54. In the present embodiment of the invention the portion 46 is illustrated as having formed therein a transverse 45 water conducting channel 67 which is adapted to conduct water to the notches 66. The plates 40 which are secured to the hood sheets extend downwardly in close proximity with the outer surface of the portion 46 and their lower edges are curved to correspond with the shape of the major portion of the outer surface of the portion 46. These plates will form effective weather seals between the top of the member 8 and the bodies 50 2 of the car regardless of the positions of the bodies relative to each other or the position of the member 8 relative to the bodies. In Fig. 12 a modification of the weather proofing construction has been illustrated in which the lower edge portions of the plates

40 extend into the channel 67 and conduct water from the hood sheets directly thereto. It will be understood that the channel 67 may, if desired, be omitted, as shown in Fig. 13.

Between the member 8 and the adjacent ends 3, rollers 68 are provided which are adjustably mounted on the end posts 12 and engage the outer surfaces of the sides 47 of the member 8. Each of the rollers is of substantially the same length as the sides 47 and at its upper end is rotatably mounted in a member 69 which member 69 is loosely mounted in a member 70 secured to the upper end portion of the post and to the plate 35. 70 At its lower end this roller is rotatably mounted in a member 71 which in turn is loosely mounted in a member 72 secured to the lower end portion of the post and to the underframe. The members 69 and 71 are 80 each provided with a horizontally disposed web 73 and vertically disposed sides 74 and 75 and vertically disposed ends 76 and 77. To connect the members 69 and 71 together a channel shaped member 78 is provided, 85 the upper end portion of which is secured to the flanges 74, 75 and 76 of the member 69, while the lower end portion is secured to the flanges 74, 75 and 76 of the member 71. 90

The members 70 and 72 are each provided with a horizontally disposed web 78a which in the case of the member 70 is secured to the plate 35, and in the member 72 is secured to the underframe 4. Each of these members is also provided with vertically disposed side flanges 79 and 80 and end flanges 81 and 82, the flanges 79 and 80 being secured to the web 13 and flange 15 respectively of the end post 12. Between the flanges 81 and 82 105 each member is provided with a bearing surface 83 which is in substantially the same horizontal plane as the bearing surface 84 of the flange 79.

Beyond the ends of the member 78 the 110 members 69 and 71 are each provided with side flanges 85 having curved bearing surfaces 86, one of which flanges in the member 71 rests on and slidably engages the bearing surface 83 of the member 72 and the other 115 rests on and slidably engages the bearing surfaces 84 of the flange 79 of the member 72. In the member 69 one of the surfaces 86 is adapted to engage the bearing surface 83 of the member 70, and the other surface is adapted to engage the bearing surface 84 of the flange 79 of the member 70. The outer side surface of the side flange 85 of each of the members 69 and 71 slidably engages with the inner surface of the adjacent flange 79 while the outer surface of each of the other flanges 85 slidably engages the inner surface of a flat plate 87 secured to a sheathing plate 88 removably secured to the flange 15 of the post 12. Interposed be- 120 125 130

tween the member 78 and a portion of the flange 15 of the post 12 are springs 89, one end of each of which is seated on a spring seat 90 which is removably mounted on the flange 15 of the end post 12, while the opposite end of each is seated in a spring seat 91 which is removably mounted on the member 78. These springs are for the purpose of forcing the rollers into close contact with the sides 47 of the member 8 at all times. It will be noted that the member 8, due to the movement of the truck and bodies relative to each other, may be rotated and also caused to swivel and that the rollers 68 will at the same time be so automatically adjusted that they will maintain weather proof connections between the member 8 and the adjacent car bodies. It will also be noted that the bearing surfaces 86 of the flanges 85 are curved for the purpose of preventing any binding action between the members 69 and 71 and the members 70 and 72 when the member 8 swivels and also to reduce the friction between these members to a minimum. It will be noted further that as the member 8 will swivel a greater distance at its upper portion than at its bottom, the bearing surface 83 of the member 70 is of greater length than the bearing surface 83 of the member 72 to take care of this greater movement. When the member 8 is removed from the bodies the springs 89 will force the member 78, roller 68 and members 69 and 71 outwardly until the end flanges 77 engage the end flanges 82 of the members 70 and 72 which engagement prevents the rollers from becoming disconnected from the bodies. Should it be desired to remove the rollers 68, the plate 88 and the plates 87 which are secured to it are first removed, the springs 89 then compressed and held compressed by means of a wire or tool engaging perforated lugs 92 formed on the spring seats 90 and 91 and when so held are removed, after which the member 78, rollers 68 and members 69 and 71 are removed as a unit.

When the adjacent ends of two bodies of an articulated unit are constructed in accordance with the invention and are operatively connected together, and the member 8 is interposed therebetween in accordance with the invention, a safe, unobstructed and weather-proof passageway is provided between the bodies, regardless of the position the bodies may assume relative to each other or to the truck.

It will be understood that changes may be made in the details and arrangement of the parts forming the invention without departing from the spirit and scope of the appended claims.

Having thus described the invention what we claim as new and desire to secure by Letters Patent is:—

65 1. In a body for an articulated car unit,

an end plate for said body having an inwardly extending recess formed by substantially horizontal and vertical plates for the reception of a portion of a passageway member. 70

2. In a body for an articulated car unit, an end plate for said body having a curved recess defined by a curved plate for the reception of a portion of a passageway member. 75

3. In a body for an articulated car unit, an end for said body having a horizontally disposed end plate, said end having a recess formed in the upper portion thereof above said end plate for the reception of a portion 80 of a passageway member. 80

4. In a body for an articulated car unit, an end wall for said body having an inwardly curved member forming a recess in the upper portion thereof for the reception 85 of a portion of a passageway member. 85

5. In an articulated car unit comprising a plurality of connected bodies, end walls for said bodies, the adjacent end walls of adjacent bodies having inwardly curved members forming recesses in their upper portions, and a passageway member partially enclosed by 90 said recesses. 90

6. In an articulated car unit comprising a plurality of connected bodies, end walls for said bodies, the adjacent end walls of adjacent bodies having members forming pockets therein and a passageway member between the adjacent ends of adjacent bodies having portions adapted to extend into said 100 pockets. 100

7. In an articulated car unit comprising a plurality of car bodies operatively connected together, a truck supporting the adjacent ends of two of said bodies, a single unitary passageway member between said ends supported by said truck and a hood projecting from each of said ends, cooperating with said member to render said ends weather-proof. 105 110

8. In a body for an articulated car unit, side plates, an end plate secured to said side plates having a notch formed therein intermediate its ends, and a member for reinforcing said end plate around said notch. 115

9. In a body for an articulated car unit, an end plate having a notch formed therein, a reinforcing member secured to said plate around said notch, and a plate secured to said member and extending outwardly therefrom, said plates and member forming a recess for the reception of a portion of a movable passageway member. 120

10. In a body for an articulated car unit, an end plate having a curved notch formed therein intermediate its ends, a reinforcing member secured to said member and passing around said notch, and end posts for said car having their upper ends secured to said member. 125

11. The combination with the adjacent ends of adjacent bodies for an articulated car unit, of a passageway member between and extending into said ends, a dome shaped roof for said member, and hoods on said ends cooperating with said roof to form a weather-proof connection between said member and bodies.

12. A passageway member for the adjacent ends of two bodies of an articulated car unit comprising a roof having the shape of a portion of a sphere, the center of which is at the lower end of said member.

13. In a passageway member for the adjacent ends of two bodies of an articulated car unit, a floor portion, a bearing for said floor portion, side portions secured to said floor portion, and a roof secured to said side portions, said roof being in the form of a portion of a sphere, the center of which is the center of said bearing.

14. In a passageway member for the adjacent ends of two bodies of an articulated car unit, a roof for said member having a water conducting channel extending there-

25 across. 15. In a passageway member for the adjacent ends of two bodies of an articulated car unit, a roof for said member having a water conducting channel adjacent its outer edge, and a water conducting channel extending across said roof.

30 16. In a passageway member for the adjacent ends of two bodies of an articulated car unit, a roof for said member, a drainage channel formed adjacent the outer edge of said roof, and a drainage channel extending across said roof and opening into the first mentioned channel.

35 17. In a passageway member for the adjacent ends of two bodies of an articulated car unit, sides for said member, a roof secured to said sides below the upper edges thereof, said sides having openings for conducting the drainage from said roof.

40 18. In an articulated car unit comprising a plurality of connected bodies, a passageway member between the adjacent ends of two of said bodies, a hood projecting from each of said ends and extending over a portion of the top of said member, means depending downwardly from said hoods adapted to cooperate with said top to provide a weatherproof connection between said bodies and said top, and antifriction means mounted on said ends adapted to cooperate with said member to provide weatherproof connections between the car body and the sides of said member.

45 19. In an articulated car unit comprising a plurality of connected bodies, a passageway member between the adjacent ends of two of said bodies, rollers between said ends and member, and means whereby one end of each of said rollers is permitted to move in

a direction toward the longitudinal center line of the car, a greater distance than the other end of each of said rollers.

20. In an articulated car unit comprising a plurality of connected bodies, a passageway member between the adjacent ends of two of said bodies, weatherproofing elements interposed between said ends and member, each of said elements comprising a roller, bearing members for said roller, 70 a member connecting said bearing members, guide members for said bearing members and resilient means for maintaining said rollers in weatherproofing engagement with said passageway member.

75 21. In an articulated car unit comprising a plurality of connected bodies, a truck supporting the adjacent ends of two of said bodies, a passageway member carried by said truck, movable weatherproofing means comprising a plurality of rollers between the sides of said member and said ends, and means for guiding said weatherproofing means.

80 22. In an articulated car body, a substantially Z shaped post forming a recess in the end of said body, weatherproofing means mounted in said recess, and removable means for maintaining said weatherproofing means in said recess.

85 23. In an articulated car unit comprising a plurality of car bodies, a passageway member between the adjacent ends of two of said bodies, posts for said ends providing recesses in said ends adjacent said member, weather- 100 proofing means for said member mounted in said recess and removable means for maintaining said weatherproofing means in said recess.

90 24. In an articulated car unit comprising a plurality of car bodies, a passageway member between the adjacent ends of two of said bodies, posts for said ends, said posts forming recesses in said ends, a passageway member between said posts, movable weather- 105 proofing means between said passageway member and each of said posts, guides for said means, and means removably mounted on said ends for maintaining said weather- 110 proofing means in said recesses.

115 25. In an articulated car unit comprising a plurality of car bodies, a passageway member between the adjacent ends of two of said bodies, rotatable weatherproofing means movably mounted in said ends adapted to engage said passageway member, and means whereby the first mentioned means may be removed or replaced without removing said passageway member.

120 26. In an articulated car unit comprising a plurality of connected bodies, a passageway member between the adjacent ends of two of said bodies, rotatable weatherproofing elements adapted to adjustably engage 125 said member, and removable means forming 130

portions of said ends adapted to maintain said elements in their proper operative positions.

27. In a car body for an articulated car unit having a recess formed in its end for the reception of a portion of a passageway member, an automatically movable member at each side of said recess adapted to maintain a weatherproof connection between said end and member, and stop means for limiting the outward movement of said member.

28. In a car body for an articulated car unit having a recess formed in its end for the reception of a portion of a passageway member, an automatically movable member, a member at each end of said movable member and movable therewith, and means secured to said body adapted to guide said members and to limit the outward movement of said movable member.

29. In an articulated car unit comprising a plurality of car bodies, a passageway member arranged between the adjacent ends of two of said bodies, floors for said bodies, each of said floors having a recess for the reception of a portion of said member and means in said recess adapted to engage with said passageway member to prevent undue swivelling movement of said member.

30. In an articulated car unit comprising a plurality of car bodies, a truck for supporting the adjacent ends of two of said bodies, a truck bolster, a passageway mem-

ber between said ends loosely supported by said bolster, a concave roof for said passageway member, hoods for said bodies and means extending downwardly from said hoods and cooperating with said concave roof to form weather seals between said roof and hoods.

31. In an articulated car unit comprising a plurality of car bodies, underframes for said bodies, a truck supporting the adjacent ends of two of said bodies, floors for said bodies, each of said floors having a recess formed therein, a member mounted on said truck and extending over the adjacent ends of said underframes between said recesses, and a passageway member pivotally mounted on said member, said passageway member extending into said recesses.

32. In an articulated car unit comprising a plurality of car bodies, a passageway member arranged between and extending into the adjacent ends of two of said bodies, an end plate for each of said bodies recessed to receive a portion of said passageway member, a horizontal plate extending over a portion of said passageway member, and a curved member secured to both of said plates and passing around a portion of said passageway member.

In testimony whereof we affix our signatures.

ALFRED K. PEHRSON.
KARL O. WINELL.
